(57) **CLAIM**

The ornamental design for a spotlight, as shown and described.

DESCRIPTION

FIG. 1 is a perspective view of the spotlight showing a new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom view thereof;

FIG. 8 is a perspective view showing the spotlight in an alternate position of use;

FIG. 9 is another perspective view showing the spotlight in an alternate position of use;

FIG. 10 is a partial enlarged perspective view of the upper portion thereof;

FIG. 11 is a partial enlarged front view of the upper portion thereof;

FIG. 12 is a partial enlarged left-side view of the upper portion thereof;

FIG. 13 is a partial enlarged left-side view of the lower portion thereof;

FIG. 14 is a partial enlarged top plan view of the left portion thereof;

FIG. 15 is a partial enlarged top plan view of the right portion thereof;

FIG. 16 is a partial enlarged bottom view of the left portion thereof;

FIG. 17 is a partial enlarged view of FIG. 8; and,

FIG. 18 is a partial enlarged view of FIG. 9.

The portions of the spotlight shown in broken lines form no part of the claimed design.
